UNITED STATES PATENT OFFICE.

ABRAHAM COOPER, OF BROOKLYN, NEW YORK.

DESIGN FOR A DINING-ROOM LIGHTING FIXTURE.

Application filed August 21, 1923. Serial No. 7,050. Term of patent 3½ years.

To all whom it may concern:

Be it known that I, ABRAHAM COOPER, a citizen of the United States, residing in the borough of Brooklyn, in the county of Kings, city and State of New York, have invented a new, original, and ornamental Design for a Dining-Room Lighting Fixture, of which the following is a specification, reference being had to the accompany-

ing drawing, forming part thereof, in which the figure is a perspective view of the dining-room lighting fixture made in accordance with my invention.

I claim:

The ornamental design for a dining room lighting fixture, as shown.

ABRAHAM COOPER.
